K. HOBBS

GASOLINE FILTER

Filed April 17, 1925

Kermit Hobbs
INVENTOR
BY Victor J. Evans
ATTORNEY

UNITED STATES PATENT OFFICE.

KERMIT HOBBS, OF SAN ANTONIO, TEXAS.

GASOLINE FILTER.

Application filed April 17, 1925. Serial No. 23,948.

To all whom it may concern:

Be it known that I, KERMIT HOBBS, a citizen of the United States, residing at San Antonio, in the county of Bexar and State of Texas, have invented new and useful Improvements in Gasoline Filters, of which the following is a specification.

This invention relates to new and useful improvements in filters and more particularly to a filter which is especially adapted for use on gasoline storage tanks of motor vehicles. The main object of my invention is the provision of a filter of the above type which is carried by an attaching sleeve 15 which may be secured to the usual flange of the filling opening in a gasoline supply tank and whereby the usual closure cap may be attached to the sleeve in the usual manner.

Another object of my invention is the provision of a filter for gasoline which will separate the dirt and water from the gasoline before the gasoline is passed into the usual storage tank and includes novel means 25 for supporting the filter within the tank.

With the above and other objects in view, my invention consists in the novel features of construction and the combination and arrangement of parts to be hereinafter more 30 fully described, pointed out in the claims and shown in the accompanying drawings, in which:

Fig. 1 is a side elevation of my improved filter showing the supporting means in section,

Fig. 2 is a top plan view with the closure cap removed,

Fig. 3 is a longitudinal section on the lines 3—3 of Figure 1,

Fig. 4 is a detailed transverse section on the lines 4—4 of Figure 1, and

Fig. 5 is a detailed section on the lines 5—5 of Fig. 2.

Referring more particularly to the drawings, the numeral 1 indicates a fragment of a gasoline storage tank having a filling opening 2 which is surrounded by an up-standing flange 3. This is an ordinary construction of a gasoline supply tank which is used on motor vehicles and upon which the usual closure cap 4 is mounted for normally closing the filling opening.

My improved filter comprises an attaching sleeve 5, having an internally threaded portion 6 which is adapted to be mounted upon the threaded flange 3 and has an in-

wardly projecting portion 7 which rests upon the upper end of the sleeve 3 and projects inwardly beyond the wall of the opening 2 forming the shoulder 8. Extending upwardly from the shoulder 8 is the threaded flange 9 upon which the usual closure cap 4 is mounted.

My improved filter comprises a body 10 having openings 11 extending longitudinally of the body and is provided with additional openings 12 at the bottom of the body. These openings 11 and 12 extend circumferentially of the body and are closed by fine mesh screen wire 13, this screen wire is of a suitable mesh to exclude the passage therethru of water and small particles but will readily permit the gasoline to pass thru the same into the tank.

The body has a circumferentially bracing portion 14 disposed between the two sides of openings 11 and 12 and in order to provide substantially bracing means for the body, rods 15 are arranged within the body as shown in Figures 3 and 4, preferably arranged in pairs opposite the screen portions 13 and spaced therefrom as shown in Figure 3. The upper ends of the rods are riveted to the wall of the body 10 above the openings 11 while the lower ends of the rods are riveted to the circumferential portion 14. These rods will not only form the brace for the body to provide a substantially rigid structure but will prevent the usual filling nozzle from coming into contact with the screen wire when filling the tank.

The upper end of the body is provided with an annular flange 16 which is adapted to rest upon the shoulder 8 and has diametrically opposed notches 17 therein and pivotally connected to the flange 16 at the opposite sides of the body are the resilient locking members 18. These locking members are pivotally connected to the flange 16 at opposite sides as shown at 19 so that the free ends of the locking members may be swung inwardly over the upper end of the body of the filter for disengaging the recessed portions 20 of the locking members from the inwardly projecting members 21 upon the inner wall of the flange 9.

It will be noted that the locking members 18 are each provided with a central indentation forming the recessed portions 20 and upon opposite sides of the recessed portions, the locking members are raised, thus in placing the filter in position within the sleeve 3,

the notches 17 are aligned with the lugs 21 to permit the flange 16 to drop downwardly onto the shoulder 8, and then by rotating the filter body the lugs 21 will ride over the locking members 18 until they are positioned between the recessed portions 20 thus retaining the filter body in position as illustrated in Figure 1. When it is desired to remove the filter body the free ends of the locking members are moved inwardly over the upper end of the body so as to disengage the lugs 21 from the recessed portions 20 and by turning the filter body until the notches 17 align with the lugs 21, the filter may be quickly and readily removed.

Upon opposite sides of the filter body, adjacent the upper end thereof, tongues 22 are struck inwardly so as to not only provide an air vent within the tank being filled, but to provide a finger piece upon the interior of the body to facilitate its removal.

It will be apparent from the foregoing that my improved device may be quickly and readily applied to gasoline storage tanks of motor vehicles, by removing the usual closure cap 4 and placing the sleeve 5 in position upon the usual threaded flange surrounding the opening. It will be apparent that a slight change may be made in the above for applying the device to storage tanks wherein the opening is normally closed by means of the plug instead of a cap illustrated in the drawings and described above.

While I have shown and described the preferred form of my invention, it will be obvious that various changes in the details of construction and in the proportions may be resorted to for successfully carrying my invention into practice without sacrificing any of the novel features or departing from the scope of the appended claims.

Having thus described my invention, what I claim is:

1. In combination with the sleeve having an inwardly extending shoulder and oppositely disposed lugs upon the interior of the sleeve and above the shoulder, a filter having an angular flange at its upper end resting

upon said shoulder, said flange having notches at diametrically opposite points to permit the passing therethru of said lugs, pivoted locking members carried by the flange and normally resting thereon, recessed portions intermediate the ends of said locking members for receiving therein said lugs, to retain the flange against movement relative to the shoulder.

2. In combination with a sleeve, an inwardly projecting angular shoulder on said sleeve, oppositely disposed lugs upon the interior of said sleeve above the shoulder, a filter body, a flange at the upper end of the body, notches in said flange at diametrically opposite points to permit the passage therethrough of said lugs, locking members pivotally connected at opposite points to the flange, said locking members having recessed portions intermediate their ends with raised portions upon opposite sides of the recessed portions, whereby upon turning movement of the filter after the lugs have passed through the notches said lugs will ride over the raised portions into the recessed portions.

3. In combination a sleeve, an inwardly projecting angular shoulder on said sleeve, oppositely disposed lugs upon the interior of said sleeve above the shoulder, a filter body, a flange at the upper end of the body, notches in said flange in diametrically opposite points to permit the passage therethrough of said lugs, locking members pivotally connected at opposite points to the flange, said locking members having recessed portions intermediate their ends with raised portions upon opposite sides of the recessed portions, whereby upon turning movement of the filter after the lugs have passed through the notches, said lugs will ride over the raised portions into the recessed portions, said locking members having their free ends moving inwardly over the upper end of the filter whereby to remove said lugs from the recessed portions.

In testimony whereof I affix my signature.
KERMIT HOBBS.
